Design for Carpet

Dec. 1357

Ebenezer Key of Lowell, Mass Assignor to Lowell Manuf. Company
Letters Patent No 1357 Dated Dec 18 1860

The schedule referred to in these Letters Patent and making part of the same
To all whom it may concern

Be it known that I Ebenezer J. Key of Lowell, in the County of Middlesex and State of Massachusetts, have originated and designed a new Pattern for Carpets or other Fabrics, of which the following is a full, clear, and exact description, reference being had to the accompanying drawings, making part of this specification.

A, is a quarter of a 12 pointed figure on which rests the shaded
surround the 12 pointed fig A. Another rosette E, rests on the springs D, and slightly overlaps A. F, in the corner is a quarter of a figure composed of four leaves resting on the shaded figure 2. The blocks 3, 4, 5, 6, 8, 9 surround the shaded figure 2, and are in turn surrounded by the lace work G. The remainder of the design is composed of regular work.
The colors employed for the different portions of the design may be varied to suit the taste and wish of the manufacturer.
